UNITED STATES PATENT OFFICE

ALBERT J. HORTON, OF WHITE PLAINS, NEW YORK, ASSIGNOR TO R. HOE & CO., INC.,
OF NEW YORK, N. Y., A CORPORATION OF NEW YORK

WEB ROLL CONTROLLING DEVICE FOR PRINTING MACHINES

Application filed April 27, 1929. Serial No. 358,481.

The present invention relates to tension devices for controlling the unwinding of web rolls used with printing machines, and it is the especial object to provide a device that will so control the roll as to automatically maintain a predetermined tension on the web running to the press; that will apply a brake to overcome the momentum of the roll and prevent it running ahead when the machine is decelerated quickly; that will act when the machine is started, to instantly remove the brake pressure previously applied to the roll to stop it, and thus avoid imposing excessive strain on the web during the starting period; and that will include means to so control the action of the mechanism that a relatively great brake pressure cannot be applied too rapidly.

It is also an object of the invention to provide a tension device for controlling web rolls, of generally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

Web roll tension devices have been used in the past in which a floating roller such as is herein shown was used to automatically operate a brake which in turn controlled the rotation of the web roll, the object being to maintain a substantially constant tension on the unwinding web, and a dash pot has been used to prevent rapid oscillation of the floating roller, as shown in Morse Patent 1,103,152 dated July 14, 1914.

In the Morse device the dash pot restrains both the rise and fall of the floating roller.

A mechanism in the same class is disclosed in Jones Patent 1,395,830, dated November 1,

1921, in which the dash pot operates to retard the rise of the floating roller but allows it to descend without restraint.

When a printing machine having the tension mechanism herein shown is running, a tightening of the web reduces the brake pressure and a slackening of the web increases it. When the machine is decelerated rapidly there is a tendency for the web roll to run ahead but the slack thus formed allows the floating roller to descend and increase the brake pressure thereby checking the rotation of the roll.

After a rapid deceleration the brake will remain applied to the roll with a heavy pressure but when the press is restarted the brake pressure will be instantly removed and thus allow the roll to rotate freely and avoid excessive strain on the web.

In the tension devices of this class that do not use a dash pot or its equivalent, under some conditions, particularly when running at certain slow speeds and with a small web roll, having but little inertia, the freely moving floating roll, will sometimes execute what has been termed a "hunting motion"; i. e., when the machine is started the floating roller will rise, relieving the brake, and the roll will run ahead due to the weight of the floating roller bearing on the web. The slack thus formed allows the roller to descend quickly and apply the brake with force sufficient to stop the roll. The continued pull of the web running to the machine then raises the floating roller and the cycle is repeated indefinitely with increasingly violent oscillation of the floating roller and it ultimately breaks the web in many instances.

The use of a dash pot connected to the support for the floating roller retards its motion and prevents the "hunting action". However, as heretofore used, it also prevents instantaneous action of floating roller to relieve the brake pressure when the machine is started, and consequently unless the brake is slackened manually, excessive strain is imposed on the web until the dash pot allows the floating roller to rise. The mechanism disclosed herein, avoids this difficulty.

In many cases the web rolls are not evenly

wound, being elliptical in section instead of circular. Due to their inertia, the rolls tend to rotate at a constant speed, and when feeding a web from a poorly wound roll it is necessary to provide means to compensate for the irregularity in the speed of the web as it unwinds. Rollers carried on spring supported bearings and around which the webs are carried have been satisfactorily used for this purpose, but when web rolls of varying size are used, it is necessary to provide a separate roller of the correct length for each width of web, for if a narrow web is run adjacent to the end of a roller adapted to carry a full width web, the pull of the web at the instant it is feeding from a low spot on the roll, will cause but one of the spring bearings to recede and in consequence one edge of the web is subjected to a strain which frequently breaks it.

A floating roller that has the required amount of free action will follow the irregularities of the running web, and when supported as herein shown is adapted to operate with either wide or narrow webs.

Figure 1 of the drawings shows one form of the invention as applied to a printing machine, and as viewed from the side of the machine.

Figure 2 shows a modified arrangement, the view being similar in most respects to Figure 1.

Figure 3 is a view partly in section and partly broken away, showing the arrangement depicted in Figure 1, and as viewed in the direction of arrow 3 of that figure.

Figure 4 is a view partly in section and partly broken away, showing the arrangement depicted in Figures 1 and 3, and as viewed in the direction of arrow 4 of Figure 3.

Figure 5 is a view partly broken away, showing the arrangement depicted in Figure 2 and as viewed in the direction of arrow 5 of that figure.

Figure 6 is a view partly in section and partly broken away showing the arrangement depicted in Figures 2 and 5, and as viewed in the direction of arrow 6 of Figure 5.

Figure 7 is a fragmentary view partly in section showing the eccentric by means of which the brake is operated.

Referring to the drawings, 11 and 11' indicate frame members of a printing machine, and 12 a bracket secured thereto which is made with a well known form of open bearing for the spindle 13, to which a web roll 14 may be secured.

A V brake sheave 15, of the usual form is secured to the spindle 13, and is engaged by the brake shoes 16, which are secured to arms 17 and 18. These arms are pivoted respectively by shafts 19 and 21, to the yoke 22, secured to the bracket 12.

The handwheel 23 has a right and left hand threaded shaft 24 which engages the corre-

spondingly screw threaded sleeves 25 and 26. The sleeve 25 is pivoted on the arm 18, and the sleeve 26 engages a stud on the arm 17. This is a well known form of hand tension device for controlling the roll as the web is drawn from it by the machine. The handwheel 28, which is also old in the art, is secured to a threaded shaft and serves to move the brake mechanism, and with it, the spindle 13, for adjusting the position of the web 75 roll axially.

The shaft 21 is free to rotate in the bracket 22, and has an eccentric portion 29, which rotates in the tub of the arm 18. Thus, by rotating the shaft 21, the pressure of the 80 brake shoes on the sheave 15 can be varied the same as by operation of the handwheel 23.

As shown in Figure 1, the web 31 is led from the roll to and around an adjustable 85 roller 32 having journals which rotate in bearings, one of which is shown at 33. These bearings slide in the brackets 34 and 34', secured to the frame 11, and are independently adjustable by means of screws 35 and 36. The position of the roller may thus be adjusted to make it bear properly against the web even though the roll in use may be larger on one end than on the other.

The web is then led to and around the floating roller 37 which is rotatably supported in the arms 38 and 38', secured to the shaft 39, which is journaled in bearings in the frames 11 and 11'. The web then passes around the roller 41, carried in fixed bearings secured to the frames 11 and 11', and is led to the printing cylinders.

An arm 42 is secured to the shaft 39, and is provided with a rod 43, on which a counter weight 44 is fitted to slide. A projection 44' on the weight engages with any one of a series of notches 45 formed on the arm 42. By turning the weight on the rod, the projection is disengaged from the notch and the weight may then be moved lengthwise on the rod and allowed to rest in another notch. By this means the effective weight of the floating roller 37 may be varied in order to regulate the tension on the web running to the machine.

A connecting rod 46 is pivotally connected to the arm 42, and to a lever 47, secured to the shaft 21. It will thus be understood that a rise or fall of the floating roller 37 will result in turning the shaft 21, and reducing or increasing the brake pressure.

A dash pot is pivoted on a stud 49 secured to the frame 11, and has a piston 51 connected to a piston rod 52, the other end of which slides in a swivel connection 53, rotatably secured to the arm 38. A collar 54 having a sleeve 54', is secured to the piston rod and provides an abutment for a relatively light spring 55, the other end of which bears against the swivel connection 53. Another 1

collar 56 is screw threaded on the end of the piston rod 52 and may be locked in place by a set screw. By turning the collar 56, the gap between the sleeve 54' and the connection 53 may be adjusted to vary the free downward movement of the floating roller.

The dash pot may contain oil or any suitable fluid and is provided with a check valve which allows the fluid to readily pass from the top of the piston to the under side, but which obstructs its passage in the reverse direction. In the preferred construction, the piston 51 is formed with openings 57 extending therethrough and a disc 58, is pressed against the openings by the spring 59, the opposite end of which is fastened to a projecting portion of the piston rod 52.

When the piston is raised the pressure of the fluid overcomes the pressure of the spring 20 and the openings allow the fluid to pass freely from the top to the bottom of the piston, but when the piston is pressed down, the disc is forced against the openings and closes them, except for a small aperture, the size of which 25 may be regulated by the adjusting screw 61, which is screwed into the piston and the end of which bears against the disc 58.

It will be seen that the floating roller may rise unrestricted by the dash pot, and that 30 by compressing the spring 55, it may also descend freely for a limited distance which is governed by the space between the upper end of the sleeve 54' and the swivel connection 53, but any further downward motion 35 is retarded by the dash pot.

It has been found that the mechanism herein disclosed can be so adjusted that the floating roller will freely follow the irregularities in the web being drawn from the roll, 40 and that the dash pot can be regulated to permit the floating roller to descend with sufficient rapidity to prevent the roll from overrunning when the press is decelerated or stopped quickly, and still act to prevent a 45 "hunting action" of the floating roller.

In the form of the invention shown in Figure 2, the floating roller is arranged to operate in the opposite direction from that shown in Figure 1, and an adjustable spring is used to vary the effective weight of the 50 floating roller. In this form the adjustable roller 32 is omitted and its function performed by the floating roller, which in this arrangement has one of its supporting arms 55 so made that it is adjustable with relation to the other arm.

As shown in Figures 2, 5 and 6, the floating roller 62 is rotatably supported in arms 63 and 63', the latter being secured to the shaft 64, which is journaled in brackets 65 and 65'. The arm 63 is adjustably connected to the arm 66 by means of the screw 67, which passes through a clearance hole in the arm 66, is provided with a thrust collar 68, and is 65 screwed into a projecting lug formed on the

arm 63. Arm 66 is secured to the shaft 64, but arm 63 may be turned on the shaft by turning the screw 67. It will be understood that this mechanism provides means for raising or lowering the arm 63 with respect to 70 arm 63', and thus compensating for any difference in the length of opposite edges of the web, due to the roll being larger on one end than on the other.

In this arrangement the dash pot is pivotally supported on the bracket 69, and the swivel connection 53 is rotatably held on one end of the arm 70, secured to the shaft 64. The other end of this arm is pivotally connected to a head formed on one end of the 80 rod 71, and the other end of the rod slides in the swivel connection 72, which is supported so as to turn in the bracket 69.

The handwheel 73 is screw threaded on the rod 71, and presses against the spring 85 74, the other end of which bears against the swivel connection 72. The spring thus tends to lift the floating roller, and may be adjusted by turning the handwheel. An adjusting collar 75 is screwed on the lower end of rod 90 71 and serves to limit the upward motion of the floating roller.

An arm 76 is secured to the shaft 64 and is pivotally connected to the rod 77, which corresponds with rod 46 of Figure 1. 95

The web is led from the roll, to and around the roller 78 which is carried in bearings fixed to the frames 11 and 11', thence around the floating roller 62 and from there to the printing cylinders. 100

It will be seen that with this arrangement, a tightening of the web will pull the floating roller down and release the brake pressure, and that when the web slackens the floating roller will rise and tighten the brake. 105

In operation, after a web roll is placed in position and the web carried around the rollers as shown, the press is started and the brake gradually tightened by means of the handwheel 23. In the arrangement shown in Figure 1, as the handwheel is screwed up, the floating roller will rise. It is so adjusted that the roller assumes the position shown in the drawings, and it is unnecessary to change the setting while the web from the roll is being run off. In the arrangement shown in Figure 2, tightening the brake by means of the handwheel will cause the floating roller to descend. 110

It will be seen that a mechanism has been provided that will act to restrain the rotation of a web roll when the web being fed therefrom slackens, and reduce the restraint when the web tightens, that will prevent a too rapid application of the restraining action, but will permit the restraint to be quickly removed when the machine is started, and will follow irregularities in the run of the web coming from the roll and maintain a substantially 115 120 125 130

constant tension on the web running to the machine.

What I claim is:

1. In a web roll controlling device, a floating roller moving transversely to its axis in response to variations in the slack of the unwinding web, a braking mechanism connected thereto, which acts to restrain the rotation of the roll when the web slackens and to reduce the restraint when the web tightens, and a retarding device arranged to permit free movement of the floating roller when the web tightens, and to restrict such movement when the web slackens. 70
15. 2. In a web roll controlling device, a floating roller moving transversely to its axis in response to variations in the slack of the unwinding web, a braking mechanism connected thereto, which acts to restrain the rotation of the roll when the web slackens and to reduce the restraint when the web tightens, and a retarding device arranged to permit free movement of the floating roller when the web tightens, and to restrict such movement when the web slackens more than a predetermined amount. 80
30. 3. In a web roll controlling device, a floating roller moving transversely to its axis in response to variations in the slack of the unwinding web, a braking mechanism connected thereto which acts to restrain the rotation of the roll when the web slackens and to reduce the restraint when the web tightens, and a retarding device arranged to permit free movement of the floating roller normally, but to restrain the movement which tightens the brake when such movement exceeds a predetermined extent. 85
35. 4. In a web roll controlling device, a floating roller moving transversely to its axis in response to variations in the slack of the unwinding web, a braking mechanism connected thereto which acts to restrain the rotation of the roll when the web slackens and to reduce the restraint when the web tightens, and a retarding device arranged to permit an extended free movement of the floating roller when the web tightens, and a limited free movement when the web slackens, but acting 100 to retard the movement of the roller when a slackness of the web permits the movement to exceed a predetermined extent. 105
40. 5. In a web roll controlling device, a floating roller moving transversely to its axis in response to variations in the slack of the unwinding web, a braking mechanism connected thereto which acts to restrain the rotation of the roll when the web slackens and to reduce the restraint when the web tightens, a retarding device arranged to permit an extended free movement of the floating roller when the web tightens and when the web slackens to permit a limited free movement, and means 110 to vary the extent of said limited free movement. 115
45. 6. In a web roll controlling device, a floating roller moving transversely to its axis in response to variations in the slack of the unwinding web, a braking mechanism connected thereto, which acts to restrain the rotation of the roll when the web slackens and to reduce the restraint when the web tightens, and a retarding device arranged to permit an extended free movement of the floating roller when the web tightens, and when the web slackens, to permit a limited free movement and an extended retarded movement. 120
50. 7. In a web roll controlling device, a floating roller moving transversely to its axis in response to variations in the slack of the unwinding web, a braking mechanism connected thereto which acts to restrain the rotation of the roll when the web slackens and to reduce the restraint when the web tightens, and a retarding device arranged to prevent rapid application of the restraining action beyond that necessary to allow the roller to follow irregularities in the running of the web as it is drawn from the roll; said retarding device being arranged to freely permit removal of 90 the restraining action when the web tightens. 95
55. 8. In a web roll controlling device, a floating roller moving transversely to its axis in response to variations in the slack of the unwinding web, a braking mechanism connected thereto, which acts to restrain the rotation of the roll when the web slackens and to reduce the restraint when the web tightens, and a retarding device arranged to permit free movement of the floating roller when the web tightens, and to restrict such movement when the web slackens, said retarding device having a moving element 100 loosely connected to one of the members that move in response to variations in the slack of the web and being so biased that the looseness will permit a limited movement of the member in one direction without such movement being restricted by the retarding device. 105
60. 9. In a web roll controlling device, a floating roller moving transversely to its axis in response to variations in the slack of the unwinding web, a braking mechanism connected thereto, which acts to restrain the rotation of the roll when the web slackens and to reduce the restraint when the web tightens, and a retarding device arranged to permit free movement of the floating roller when the web tightens, and to restrict such movement when the web slackens, said retarding device having a moving element 110 loosely connected to one of the members that move in response to variations in the slack of the web and being so biased that the looseness will permit a limited free movement of the floating roller in the direction which restrains the roll. 115
65. 10. In a web roll controlling device, a suitably supported floating roller moving trans- 120

versely to its axis in response to variations in the slack of the unwinding web, a braking mechanism connected thereto, which acts to restrain the rotation of the roll when the web slackens and to reduce the restraint when the web tightens, and a retarding device arranged to permit free movement of the floating roller when the web tightens, and to restrict such movement when the web slackens, said retarding device comprising a dash pot having a piston with a piston rod loosely connected to the floating roller support and so biased that the looseness will permit a limited movement of the roller support, unrestricted by the dash pot.

11. In a web roll controlling device, a floating roller moving transversely to its axis in response to variations in the slack of the unwinding web, a braking mechanism connected thereto which acts to restrain the rotation of the roll when the web slackens and to reduce the restraint when the web tightens, and means arranged to permit sufficient free movement of the floating roller to allow it to follow irregularities in the running of the web as it is drawn from the roll, but restraining the movement which tightens the brake, when such movement exceeds a predetermined extent.

12. In a web roll controlling device, a floating roller moving transversely to its axis in response to variations in the slack of the unwinding web, a braking mechanism connected thereto, which acts to restrain the rotation of the roll when the web slackens and to reduce the restraint when the web tightens, and means for varying the pressure of the floating roller on the web; said means including an arm having a rod, a weight slideable thereon, and locking means on the arm engaging the weight to hold it in position, said locking means being disengageable by turning the weight.

13. In a web roll controlling device, a floating roller moving transversely to its axis in response to variations in the slack of the unwinding web, a braking mechanism connected thereto, which acts to restrain the rotation of the roll when the web slackens and to reduce the restraint when the web tightens, a device arranged to retard excessive action of the floating roller in one direction, and means for varying the pressure of the roller on the web; said means comprising an arm having a rod, a weight slideable thereon and locking means on the arm engaging the weight to hold it in position, said locking means being disengageable by turning the weight.

60 In testimony whereof, I affix my signature.
ALBERT J. HORTON.
